(57) **CLAIM**

The ornamental design for a bottle, as shown and described.

DESCRIPTION

FIG. 1 is a top perspective view of a bottle showing my new design;

FIG. 2 is a front elevation view thereof, the left side, right side and rear elevation views being identical;

FIG. 3 is a top plan view thereof, shown at an enlarged scale; and,

FIG. 4 is a bottom plan view thereof.

The bottle is used to contain liquids. The broken lines shown in the drawings are for illustrative purposes only and form no part of the claimed design.
